UNITED STATES PATENT OFFICE.

EDWARD B. STARR AND HOWARD E. MARSH, OF LOMPOC, CALIFORNIA.

APPARATUS FOR CUTTING BRICKS OR BLOCKS FROM NATURAL DEPOSITS.

1,392,459.

Specification of Letters Patent.

Patented Oct. 4, 1921.

Application filed January 31, 1921. Serial No. 441,346.

To all whom it may concern:

Be it known that we, EDWARD B. STARR and HOWARD E. MARSH, citizens of the United States, residing at Lompoc, in the 5 county of Santa Barbara, State of California, have invented a new and useful Improvement in the Apparatus for Cutting Bricks or Blocks from Natural Deposits, of which the following is a specification.

10 This invention relates to the art of sawing or cutting bricks or blocks from natural deposits or beds of kieselguhr or other material, and an important object of the invention is to provide for cutting such bricks 15 or blocks rapidly and economically.

A further object of the invention is to provide improved apparatus for effecting such cutting operation in the most efficient and convenient manner.

20 The present invention relates to improved means for cutting bricks or blocks from natural deposits according to the method set forth in Patent No. 1,353,188 granted to us September 21, 1920.

25 The accompanying drawings illustrate apparatus embodying our invention, and referring thereto:

Figure 1. is a plan view of one form of such apparatus.

30 Fig. 2. is an end elevation thereof.

Fig. 3. is an end view of a different form of saw head for use with this apparatus.

Fig. 4. is a side elevation of the saw head shown in Fig. 3.

35 Fig. 5. is a side elevation of the apparatus shown in Fig. 1.

Fig. 6. is a section on line 6—6 in Fig. 5.

40 Figs. 7. and 8. are diagrams showing the manner in which the cutting operations are performed.

We have found it desirable, in cutting bricks or blocks from beds of kieselguhr, or other naturally occurring deposits, by the method set forth in our patent aforesaid, to 45 carry on the operation in such manner that a series of vertical cuts are first formed in the vertical face of the bank or bed, followed by horizontal cuts in the face and bricks or blocks are severed from the face.

50 by vertical cuts parallel to the face. These operations may be conveniently performed by two machines, one for making the vertical cuts into the bank-face, and the other machine for making the horizontal cuts into the bank face and for severing the bricks or blocks from the face. Such two machines

may be of similar design, differing only in the saw head or cutter head thereof, and, in fact, a single machine could be used with interchangeable saw heads, but for the sake 60 of economy and expedition in operation it is desirable to use two machines.

Referring to Figs. 1, 2 and 5 the machine shown therein comprises a truck or vehicle having a body or frame or operation platform 1 mounted on wheels 2 adapted to run on track rails 3, said truck being provided with suitable means for moving along the track and with means movably mounted on the truck frame to support the cutting devices. We have shown for this purpose a drive connection including an electric motor 4 having suitable gearing connected to the truck wheels, but any other suitable means (for example, cable traction) may be used. 70 The same motor may be used to operate the cutter shifting means, as hereinafter described.

Two guide members 6 are rigidly secured to truck body 1 and project therefrom laterally to form guiding and supporting means for a slide member 7 for supporting the cutter head, said member 7 being provided with sleeves 8 mounted to slide on said guide members. Said members 6 and 8 80 may, as shown, be tubular in form. A screw shaft 9 extends between and parallel to the guide members 6 being mounted at one end in bearings 10 on body 1 and at the other end in a bearing 11 on a cross bar 12 connecting the outer ends of members 6, said screw shaft having connections to operate the cutter head. Said shaft 9 is also preferably used as a drive shaft for the truck 85 wheels 2, a clutch 13 being mounted on said shaft and controlled by lever 18 and adapted to connect the shaft to gear members 14 loose on the shaft and connected by chains 15 to sprocket wheels 16 on the shafts 17 of wheels 2. Shaft 9 may be operated in 90 either direction by driving connection from the motor 4, whose shaft is connected by chain 20 to a sprocket wheel 21 on a counter shaft 22 mounted in bearings 23 and 24, and provided with clutches 25 and 26 controlled 100 alternatively by a control lever 27, to connect shaft 22, either to a wheel 28 connected by a chain 29 to a sprocket wheel 30 on shaft 9, or to a gear wheel 31 meshing with a gear wheel 32 on shaft 9.

110 Slide member 7 is provided with vertical bearing guides 33 in which slide vertically

two vertical frame members 36 (preferably tubular) which are connected at their lower ends by a cutter head 37, said members 36 and 37 constituting a cutter-frame on which 5 are mounted the sawing means. Members 36 are provided with vertical racks 38 engaging gear wheels 39 on a shaft 40, which is mounted in bearings 41 on slide member 7. A worm wheel 42, loose on shaft 40, and 10 engaged by the screw or worm 43 on shaft 9 can be clutched to shaft 40 by a clutch 44 so that rotation of said wheel by the worm 43 will operate the shaft 40, gear wheels 39 and racks 38 to move the cutter head frame 15 up or down.

Another worm wheel 46 engaging worm 43 is loose on shaft 47 which is rigidly mounted on the member 7 so that by clutching the wheel 46 to said shaft 47 by means 20 of a clutch 48, the worm wheel 46 is locked in position and from rotation and serves as a nut coöperating with the worm or screw 43, so that rotation of shaft 9 operates through members 43 and 46 to move the 25 slide member 7 outwardly or inwardly along the guide means 6. The clutch devices 44 and 48 are controlled, through rods 50 and 51 and clutch levers 52 and 53 respectively, from control levers 54 and 55 adjacent to 30 the truck body 1, on which the operator is stationed, said rods 50 and 51 (see Fig. 6) having longitudinal slots 56 engaging with keys 57 in sleeves 58, carrying the levers 52 and 53 so as to maintain controlling connection to said levers as the slide member 7 35 moves longitudinally in guide means 6.

In order to accurately space and hold the slide member 7 in proper position on the guide means 6, the latter is provided with 40 holes 60 spaced apart along the length thereof, according to the width of the brick or block to be cut, and adapted to receive a locking or stop pin 61 which engages with one end of the slide member 7 or with a 45 hole 62 therein, to hold said member in position. Similarly each of the vertical frame members 36 may have a series of holes 63 to receive locking or stop pin 64 to engage the bearing or guide 35 so as to retain the 50 cutter head at any desired height.

The apparatus shown in Figs. 1, 2 and 5 is adapted for making horizontal cuts into the bank face and for severing blocks or bricks, the cutter head 37 being provided 55 with horizontal saws 66 carried by vertical shaft 67, and with a vertical cut off saw 68 carried by one or the other of two horizontal shafts 69, said shafts 67 and 69 being mounted in bearings 70 and 71 on the cutter head. 60 Three of the horizontally cutting saws 66 are shown, so spaced on shaft 67 as to simultaneously cut three grooves or kerfs, spaced apart the thickness of a brick, for example, and the saw 68 extends approximately in the 65 plane parallel to the bank face and tangent

to the peripheries of saws 66, so as to make a severing cut at the inner ends of the cuts made by the saws 66. A motor 74, preferably an electric motor, is mounted on the cutter head and is connected to the saw 70 shaft 67 by bevel gears 77 and 78 and to shafts 69 by suitable gearing, including a gear wheel 79 geared to the motor shaft and sprocket chains 76 engaging sprocket wheels on the shafts 69 and on the motor shaft, and 75 on the shaft of wheel 79, so as to drive shafts 69 in opposite directions.

In conjunction with bank cutting apparatus above described we provide a face cutting means, consisting, for example, of a 80 truck having horizontally extending guide means and a slide member mounted to move them laterally to the movement of the truck on the track rails, and carrying the vertically movable frame from the cutter head, 85 all of such parts being preferably of the same construction and mode of operation as in the case of the bank cutter, the only difference in the two machines being in the construction of the cutter head, which, in 90 the case of the face cutter, is provided, as shown, in Figs. 3 and 4, with a series of vertical saws 80, carried by a shaft 81 mounted in bearings 82 on the cutter head, and driven by sprocket chain connection 83 95 from an electric motor 89 on the cutter head. The saws 80 are spaced apart, for example, a distance equal to the length of the brick or block to be cut. Suitable electric operating circuits are provided for the 100 several motors above referred to and are provided with suitable controlling means, not shown, located preferably on the truck frame or operator's platform 1.

The operation of the apparatus is as follows: The track rails 3 having been laid on the top of the bank to be cut and adjacent and parallel to the vertically extending face thereof, the face cutting machine is brought into position on the truck, at the place 110 where the operations are to start, this position being indicated at A in Fig. 7. While the bank face, for purpose of explanation, is assumed to be vertical, it will generally be more or less inclined to the vertical, according to the dip of the strata being cut, 115 said face being generally perpendicular to the top of the strata.

An operator is stationed on the truck frame to operate the various motor and 120 clutch controls, and an attendant is stationed at the bank face to direct the operator in setting the cutter head and to lock the cutter head when set. Motor 4 is set in operation by suitable electric control means 125 and the operator on the truck frame moves the clutch lever 27 to cause the worm shaft 9 to turn in proper direction. By then operating clutch control lever 55 the lower worm wheel 46 is locked to its shaft 47 and 130

- acts as a nut on the worm or screw 43, causing the slide member 7 with the cutter frame and head carried thereby to move in or out on the guide means 6, so as to bring the vertical screws 80 over the edge portion of the bank and in position to make vertical cuts in the bank face of depth equal to the width of a brick or block. The saws 80 are then set in operation by means of motor 89, and 5 the cutter head is caused to descend by operating lever 54 to throw in the clutch connection from worm 43 to shaft 40 of gear wheel 39 engaging racks 38, so that rotation of worm shaft 9 will operate the cutter head 10 downwardly and cause a series of vertical cuts to be made in the bank face, this operation being indicated by the lines *b* in Fig. 7. It will be understood that the worm shaft 9 at this time, and in fact throughout the operation 15 of the machine, is rotated by means of motor 4, the clutch lever being operated to control movement of said shaft in the desired direction, but the clutch 13 for the drive connection to the truck wheels being released except when the machine is to be moved along the track 3. Clutch 48 is also released so that worm wheel 46 turns freely on its shaft, and the slide member is held from movement along the guide means by 20 the friction of its bearings on said guide means. This vertical cutting operation having been performed, control lever 54 is operated to disengage the clutch 44 from the upper worm wheel 42 and lever 55 is operated to connect the clutch 48 to the lower worm wheel 46 and the same shaft 9 being then operated to cause the cutter head frame to move outwardly to disengage the saw from the bank face. Clutch lever 18 is then 25 operated to control the connection to the truck wheels so as to cause the machine to advance along the track in position to cut another vertical series of kerfs in the bank face, the path of the saws 80 in this operation being indicated at *c* in Fig. 7, and the several clutch levers are then operated to cause the saws 80 to cut into the bank face and to ascend thereon so as to make vertical cuts as indicated at *b'* in Fig. 7; the 30 machine being then advanced along the track to move the saws (as indicated at *c'* in Fig. 7) to a new position, this operation being repeated until the end of the bank is reached.
- 55 The bank cutting machine, illustrated in Figs. 1, 2 and 5 follows the face cutting machine described and, by suitable control of its motors and clutch levers, is caused to advance along the track, the cutter head 37 being set so as to enable the saws 66 to make a plurality of horizontal cuts, indicated at *d* in Fig. 8 (in this case three) corresponding in depth to the width of the brick or block and spaced apart the thickness of the brick or block, and the cut off saw 68 being placed 30 on that one of the shafts 69 which at that time is at the rear of the saws 66 so as to sever the bricks or blocks from the bank and permit them to fall away, or to be removed, from the bank. When the end of the bank 70 is reached the cut off saw is placed on the other shaft 69, the cutter head being lowered along line *e* (Fig. 8) and the operation of the machine is reversed, to cut and sever three more horizontal rows of bricks, the 75 portion of the bank thus operated on being indicated at *d'*; the above described operation being repeated until the bank is cut to its full depth, the whole operation being then repeated to cut off successive rows of 80 bricks or blocks from the bank face, the track rails being moved back from time to time, when necessary.
- What we claim is:
1. An apparatus for cutting bricks or blocks from a natural bank of material comprising a vehicle adapted to move parallel to the bank face, guide means extending laterally from said vehicle, a slide member mounted to slide on said guide means, motor-driven controllable means for moving said slide member along said guide means, a cutter head mounted on said slide member to move vertically thereon, sawing means carried by said cutter head, and motor-driven controllable means for moving said cutter head vertically on said slide member. 90
  2. An apparatus as set forth in claim 1, in which said cutter head is provided with a plurality of horizontally extending saws 100 and with a vertically extending saw for sawing off simultaneously the bricks or blocks cut by the said plurality of horizontally extending saws. 95
  3. An apparatus for cutting bricks or blocks from a bank of material, comprising a vehicle, guide means extending laterally from the vehicle, a slide member mounted to move on said guide means, a cutter head frame mounted to move vertically on said slide members, saw means carried by said cutter head, a motor carried by said cutter head frame and connected to operate said saw means, a motor on said vehicle, a shaft mounted to turn on said vehicle and extending parallel to said guide means, and having reversible driving connections with said motor, a releasable operating connection between said shaft and said slide member frame to move the slide member along said guide means by operation of said shaft, and a releasable operating connection between said shaft and said cutter head frame to move said cutter head frame vertically by operation of said shaft. 110
  4. An apparatus for cutting bricks or blocks from a bank of material, comprising a vehicle, guide means extending laterally from said vehicle, a slide member mounted to move on said guide means, a cutter frame 120

provided with sawing means and mounted to move vertically on said slide member, a shaft mounted to turn on said vehicle and provided with a worm means for reversibly driving said shaft, a worm wheel member mounted to turn on said slide member and engaging said worm, clutch means for locking said worm wheel from rotation to enable it to act as a nut on said worm, to cause the slide member to be moved along said guide means, a second worm wheel engaging with

said worm, and means including a clutch and gearing connecting said second worm wheel to said cutter frame to move said cutter frame vertically by operation of said shaft.

In testimony whereof we have hereunto subscribed our names this 11th day of January, 1921.

EDWARD B. STARR.
HOWARD E. MARSH.
